TRIM PIECE FOR AUTOMOBILES

Richard F. Baird, Royal Oak, Mich., assignor to Chrysler Corporation, Highland Park, Mich., a corporation of Delaware

Application May 11, 1955, Serial No. 35,919

Term of patent 7 years

(Cl. D14—27)

Fig. 1 is a side elevational view of a trim piece for automobiles showing my new design wherein the broken lines indicating an automobile are for illustrative purposes only;

Fig. 2 is a side elevational view of a trim piece for automobiles on a slightly larger scale;

Fig. 3 is a top plan view thereof; and

Figs. 4, 5 and 6 are sectional views taken on lines 4—4, 5—5 and 6—6 of Fig. 2.

The characteristic features of my design reside in the portions shown by means of full lines in the drawing.

I claim:

The ornamental design for a trim piece for automobiles, substantially as shown and described.
